ATTY'S.

UNITED STATES PATENT OFFICE.

MAX COHEN, OF REVERE, MASSACHUSETTS.

ARTICLE-STAND.

1,327,943.

Specification of Letters Patent.

Patented Jan. 13, 1920.

Application filed December 8, 1917. Serial No. 206,133.

To all whom it may concern:

Be it known that I, MAX COHEN, a citizen of the United States, residing at Revere, in the county of Suffolk and State of Massachusetts, have invented new and useful Improvements in Article-Stands, of which the following is a specification.

This invention is an article stand or holder embodying such a construction as will accommodate and maintain a shoe cleaning brush and will receive and support umbrellas, canes, or the like. The stand is adapted to be installed on a horizontal support, such as a floor or a door step, and is provided with a drawer, which is to receive the dirt falling from the shoe brush, supported by the stand, and to receive the drainage from the umbrellas.

The invention will be hereinafter fully set forth and particularly pointed out in the claims.

In the accompanying drawings:

Figure 1 is a top plan view of a shoe cleaner embodying the invention.

Fig. 2 is a section on line 2—2 of Fig. 1.

Fig. 3 is a section on line 3—3 of Fig. 1.

The same reference characters indicate the same parts in all of the figures.

The stand or holder is of a unitary construction, being cast or of sheet metal, and comprises parallel side walls 20, having means such as perforated ears 19 adapted to be attached by screws to a flat support S, and a curved transverse end wall 21 connecting the side walls and forming a closed end of the holder.

The lower edge of the side portions 20 constitute guides between which a drawer 22 is adapted to slide upon the support S, and to receive dirt falling from a brush adapted to be received and supported by the stand at a suitable height above the drawer. The inward movement of the drawer is limited by the end wall 21^a. However, it is freely movable in the drawer-way and readily removable therefrom. A traverse partition wall 21, preferably of a curved formation, is provided between the walls 20 at a relatively short distance from the end wall 21^a and has its lower-edge terminating above the drawer-way, as is clear from Fig. 2. To support a shoe cleaning brush, I provide the side walls 20 of the holder with inwardly projecting horizontal flanges 23, and the partition 21 with an inwardly projecting horizontal flange 24, these flanges being on the same

level and at a suitable distance above the drawer-way, as shown by Figs. 2 and 3. The flanges 23 and 24 may be in practice, parts of a single U-shaped flange, although it is obvious that they may be made separate from each other. The said flanges are narrow, so that they do not obstruct the dirt falling from the brush into the drawer 22.

The side walls 20 are provided with inwardly projecting vertical flanges 25, which are arranged to abut against the outer ends of the sides 12 and the bottom 14 of the brush. The upper portions of the side and end walls 20 and 21, and the flanges 23, 24 and 25 constitute a brush receptacle adapted to removably hold the brush, and prevent horizontal displacement thereof in any direction, said receptacle having a dirt-releasing bottom formed by the flanges 23 and 24. The frame or holder is bottomless, so that the drawer is supported by and movable on the support S.

The invention further includes a substantially horizontal plate or ledge 27 provided between the walls 20, 21, and 21^a adjacent the upper edges of the same and supported thereby. The plate 27 has sockets 28 therein, each adapted to receive the tip 29 of an umbrella and to hold the latter in a vertical position, so that it may drain into the drawer 22 which projects under the plate 27 and the tips of the umbrellas may rest on the bottom thereof as shown by Fig. 2. Any desired means may be provided for permitting drainage of the plate 27. In the drawing the sockets 28 are shown as formed with grooves 30 and the plate is provided with holes 31.

Any suitable form of shoe brush may be used. However, one style of brush is shown for the purpose of illustration, and consists of a bottom section 14, side sections 12 and an end section 13, all having inwardly extending brush tufts 16 and the bottom section having an opening 15 through which dirt passes from the brush to the drawer 22 below.

When the brush is in place, its closed end 13 bears against the end wall 21 of the holder, its bottom portion rests on the flanges 23 and 24, and the ends of its side portions 12 abut against the side wall 20 of the holder and vertical flanges 25. The brush is therefore supported against sideways and endwise displacement and may be readily lifted from the holder.

I prefer to provide the holder with a transverse web or plate 26, constituting a scraper which is spaced from the vertical flanges 25 sufficiently to permit dirt dislodged from a shoe bottom to fall into the drawer 22. The drawer is of such length that its outer end projects outwardly from the scraper, as shown by Fig. 2, and is adapted to receive dirt falling from the outer side of the scraper.

10 The drawer may be provided with a handle 32 to facilitate its manipulation.

Cross bars 33, Figs. 2 and 3, may be provided between the flanges 23, to additionally 15 support the bottom portion 14 of the brush.

I claim:

1. As a new article of manufacture, an article stand of a unit construction, comprising a frame provided with parallel side walls and one end wall, the other end being open; the lower portion of the side walls forming a drawer-way, means within the frame for supporting a brush above the drawer-way and permitting communication 20 to the latter, and a partition wall spaced 25 to the bottom portion of the brush.

from the end wall and terminating above the drawer-way, said end wall and said partition being connected by a perforated top member.

2. As a new article of manufacture, an article stand of a unit construction, comprising a frame provided with parallel side walls and one end wall, the other end being open; the lower portion of the side walls forming a drawer-way, means within the 30 frame for supporting a brush above the drawer-way and permitting communication to the latter, and a partition wall spaced from the end wall and terminating above the drawer-way, said end wall and said 35 partition being connected by a perforated top member, and a drawer slidably in said drawer-way and having its inward movement limited by said end wall, whereby the compartments on each side of said partition 40 are over said drawer.

In testimony whereof I have affixed my signature.

MAX COHEN.
